UNITED STATES PATENT OFFICE

2,451,108

TOILET VENTILATING MEANS

Caleb M. Molpus, Memphis, Tenn.

Application October 24, 1946, Serial No. 705,377

8 Claims. (Cl. 4—213)

1

My invention relates to toilet ventilating means, and it is an object of the same to provide improved means for drawing off odors from a toilet, which means shall be simple and inexpensive, while being inconspicuous and not likely to get out of order.

Another object is to provide a device of the character indicated, with means for normally closing off the communications to the outer atmosphere, but which shall be automatically reopened under certain conditions.

Another object is to provide an electric fan forming a part thereof, and having improved circuit-closing means operated by a toilet seat.

Another object is to provide an improved toilet bowl construction whereby odors may be withdrawn therefrom.

Referring to the drawings, which are made a part of this application for patent, and in which similar reference characters indicate similar parts:

Fig. 1 is a plan of the device of my invention, with parts omitted for clearness,

Fig. 2 is a front elevation, with parts broken away,

Fig. 3 is a side elevation with parts broken away, and

Fig. 4 is a detail, partly in section, showing parts of the toilet bowl and cover.

In the drawings, reference character 10 indicates generally a toilet bowl having a cover 11 hinged to the bowl near the rear thereof in any desirable or conventional manner. The bowl has a circumferential passage molded in the upper part of its outer wall at 12, said passage communicating with the interior of the bowl by way of a plurality of small ports 13, the circumferential passage terminating at the rear of the bowl in a rearward passage 14 leading to a pipe 15 connecting the passage 14 to a casing 16 for a motor and a fan operated thereby. A light-weight ball check-valve 17 may be located in the slightly inclined passage 14, so as normally to close the same at its point of connection with the annular passage 12, this valve being light and small enough to be moved to the right in Fig. 4 and permit air from the bowl to be drawn past it by the suction of the fan hereinafter described. A water supply pipe is indicated at 18.

The casing 16 is located on a shelf 19 behind the bowl, inside a housing 20 having a rear access door 21, the motor 22 being supported on an inclined track 23 fixed to said shelf, and the motor frame having rollers 24 at its under side running on said track to the extent permitted

2

by the upturned ends 24 of the track members 23. The motor shaft 25 has a fan fixed coaxially thereon at its higher end, which fan draws air through the pipe 15 and forces it out of the casing through a fitting 27 leading to a vent pipe 28 which conducts the air either upward or downward to the outer air or to a furnace or otherwise disposes thereof.

The motor is driven by means of a circuit connected at 29 to any suitable source of power, said circuit comprising conductors 30 and 31 adapted to be connected by means of a mercury switch 32 to actuate the motor 22. The switch is located in an inclined portion of the tiltable seat, so that when the seat is pressed down by the weight of a person the circuit will be closed and the motor and fan set in operation.

The fitting 27 has a tapered seat at its end nearest the motor, and the motor casing carries a tapered plug valve 27' adapted to seat therein and so to close the passage between the vent 28 and casing 16, thus preventing air from passing in either direction through said fitting. It will be evident that when the mercury switch is closed the motor will rotate, causing the fan to rotate and draw air from the bowl, at the same time pulling the motor to the right in Fig. 2 so as to open the passage to the vent pipe, whereupon air is forced out of the casing 16 to the vent pipe. The seat 27 may be normally held in raised position by means such as a spring (not shown), and when raised after having been depressed the circuit will be broken at switch 32, the motor and the fan will stop, and the gravity action of the motor and associated parts will cause them to move down the track and so to close the port in fitting 27. The ball check valve 17 may be omitted, but if used it will close the left-hand end of passage 14 when the device of my invention is not in use, being drawn to the right to open the passage by the suction of fan 26 when the motor is running.

It will be obvious to those skilled in the art that many variations may be made in the devices herein shown and described, all without departing from the spirit of the invention; and, therefore, I do not limit myself to what is shown in the drawings and described in the specification, but only as indicated in the appended claims.

Having thus fully described my invention, what I claim is:

1. In combination with a toilet bowl, a normally elevated toilet seat, a casing, a track in the casing, a motor movable along said track, inlet and outlet ports adjacent opposite ends of said track,

connections from the inlet port to the interior of the bowl, a valve on the motor for closing the outlet port, a fan driven by the motor and arranged to move the motor along the track and thus to open the outlet port when the motor is in action, means biasing the motor to travel in the opposite direction and thus to close the outlet port when the motor is deenergized, and a circuit for the motor including a switch that is closed upon depression of the seat.

2. In combination, a toilet seat, a toilet bowl having an air passage formed therein and communicating with the interior of the bowl, a casing, a track in the casing, inlet and outlet ports in the casing adjacent opposite ends of the track, connections from the inlet port to said air passage, a motor movable along said track, a valve traveling with the motor to close the outlet port, a fan driven by the motor and arranged to move the motor along the track so as to open the outlet port when the motor is energized, means biasing the motor to travel in the opposite direction along the track when the motor is deenergized, and a gravity actuated valve so located as to close the passage to the inlet valve in the absence of suction in said passage.

3. Ventilating means comprising a casing, a track in the casing, inlet and outlet ports in the casing adjacent opposite ends of said track, a motor traveling on said track, a valve movable with the motor in its travel, said valve closing said outlet port when the motor is out of action, a fan driven by the motor and arranged to move the motor along the track and thus to open the outlet port, and means biasing the motor to travel toward the outlet port and thus to close said port when the motor is out of action.

4. A device as in claim 3, including a vent pipe in communication with said outlet port, a housing for concealing said vent pipe, and an access door to said housing.

5. Ventilating means comprising a casing, a track therein, inlet and outlet ports at spaced points with reference to said track, a motor movable along said track, a valve movable with the motor in its travel along said track, a fan driven by the motor and tending to move the same in a direction for opening the outlet port, and means biasing the motor to move in a direction to close the outlet port when the motor is deenergized.

10 6. A device as in claim 5, wherein the motor shaft is parallel to the track, and the fan and valve are mounted respectively upon opposite ends of the shaft.

15 7. A device as in claim 5, wherein the track slopes downward from the inlet end of the casing toward the outlet ends thereof.

8. Ventilating means comprising a casing, a port in the casing, a valve movable to open and close the port, a motor movable with the valve, a fan driven by the motor and moving the same and the valve in a direction for opening the port, and means biasing the motor to move the same and the valve in a direction to close the port when the motor is deenergized.
